UNITED STATES PATENT OFFICE.

ARTHUR J. LEWIS, OF STRATFORD, CONNECTICUT, ASSIGNOR TO THE BAIRD MACHINE COMPANY, OF BRIDGEPORT, CONNECTICUT, A CORPORATION OF CONNECTICUT.

CHUCKING MACHINE.

Application filed May 5, 1923. Serial No. 636,856.

This invention relates to metal working machines and particularly to the type in which there are a plurality of work carrying spindles, with one or more tools and means for causing relative movement between the spindles and the tools to perform the required operations, and also whereby a plurality of operations may be performed at the same time or in succession.

10 It has for an object to provide a machine of this type in which there is an improved mounting for the work carrying spindles, and an improved support for the tools whereby the proper relation between the spindles and 15 the tool holders is properly maintained.

It is another object of the invention to provide an improved feeding means for the tools, and so arranged that if desired where a plurality of tools are used they may be given different rates of feed and also different lengths 20 of stroke.

It is a further object of the invention to so mount the spindles, the driving means therefor, the tool support and the tool feeding means that the work carrying chucks and 25 the tools are easily accessible at all times.

It is another object of the invention to provide an improved driving means for the work carrying spindles and one in which the individual spindles may be operated at different 30 speeds if desired.

It is a still further object of the invention to provide a machine of this type in which at the end of a cycle the drive for the indexing mechanism will be automatically disconnected so that should the operator not have finished removing the finished piece or inserting a new piece, indexing of the spindles will not take place until the operator is prepared 40 for the same.

With the foregoing and other objects in view, I have devised the construction illustrated in the accompanying drawings, in which

45 Fig. 1 is a front side elevation of the machine, portions of the same being broken away to more clearly show the construction.

Fig. 2 is an end view of the machine looking from the right of Fig. 1.

50 Fig. 3 is a transverse section substantially upon line 3—3 of Fig. 1.

Fig. 4 is a longitudinal section through the tool support, showing the tool feeding means.

55 Fig. 5 is a transverse section thereof substantially on line 5—5 of Fig. 4.

Fig. 6 is a detailed layout of the main driving means showing the speed changes therefor and also the means for driving the tool feeding means and the speed changing means therefor, the shafts being shown in a common 60 plane.

Fig. 7 is a view from the right of Fig. 6 showing the proper relative positions of the shaft comprising the tool feed driving means.

Fig. 8 is a top plan view of the main friction drive.

Fig. 9 is a top plan view of a ratchet drive taken substantially on line 9—9 of Fig. 6.

Fig. 10 is a transverse detail view immediately in front of the chucks for carrying 70 the work, showing the turret indexing means.

Fig. 11 is a side view thereof looking from the right of Fig. 10.

Fig. 12 is a transverse detailed sectional view substantially on line 12—12 of Fig. 1.

Fig. 13 is a partial side elevation and partial sectional view taken substantially on line 13—13 of Fig. 12.

Fig. 14 is a detailed sectional view substantially on line 14—14 of Fig. 13.

Fig. 15 is an end view showing the details of means for changing the speed of the individual work spindles.

Fig. 16 is a detail sectional view thereof substantially upon line 16—16 of Fig. 15.

Fig. 17 is a view transversely of the machine substantially upon line 17—17 of Fig. 1, showing the hand indexing device.

Fig. 18 is a front view of this device looking from the left of Fig. 17.

Fig. 19 is a top plan detailed view of the means for automatically increasing the speed of rotation of the tool feed drum for returning the tools to their original position at the end of the cycle and looking downwardly on 95 Fig. 17, and

Fig. 20 is a detailed sectional view of the hand operated device for stopping the feed and indexing mechanism on an enlarged scale.

In the embodiment shown the machine comprises a bed 20 mounted on suitable legs 21 and 22, the bed being dished as shown at Fig. 3 to catch the oil used in the various operations to be performed. Mounted within the bed is 105 the frame indicated generally at 23 in which are mounted the various mechanisms. Intermediate its ends the frame is provided with a bearing 24 for the rotatable spindle carrying turret 25, and suitable means is provided for 110

at given intervals rotating this turret by a step by step motion for the indexing operation, which mechanism will presently be described.

Mounted to rotate in the turret are a plurality of work carrying spindles 26, in the present case six of these spindles being shown, and each one is provided with a chuck 27 for carrying the work. At the rear end of the turret each spindle is provided with a toothed clutch block 28 adapted for engagement with a block 29 having similar teeth carried on the end of a spindle drive shaft 30. These spindle drive shafts are adapted for longitudinal movement toward and from the clutch blocks 28 for the purpose of disconnecting blocks 28 and 29 when the turret is rotated and to then connect these blocks for driving the spindles. The spindles 26 rotate at their forward ends in bushings 31 in the turret and at the rear ends in the bushings 32. To the rear end of each spindle is secured a block 28, a suitable adjusting screw 33 being threaded in the turret embracing the spindle and engaging the end of the bushing 32 for properly positioning the spindle in the turret, and a chuck 27 being connected to the forward end of each spindle.

The means for shifting the spindle drive shafts 30 for connecting and disconnecting the clutch blocks 28 and 29 is shown in detail in Figs. 12, 13 and 14. As the operation of inserting and removing the work is to be made while various machining operations are being performed on the work, only five of the spindles are driven, the sixth spindle being stationary to allow insertion and removal of the work. The spindle drive shafts 30 have two bearings 34 and 35 in the frame 23 of the machine adjacent the ends of these shafts, and to the rear of the portion of the frame carrying the bearings 35 is a bracket 36 secured to the frame by suitable screws 37. This bracket has a flange 38 provided with openings 39 to receive the ends of the spindle driver thrust pins 40, these pins having a flange 41 between which and the flange 38 are suitable ball thrust bearings 42. The end of each pin 40 extends into a longitudinally extending opening in the shafts 30 in which is a coiled spring 43, this spring reacting at its opposite ends on shaft 30 and the end of the pin 40, and will thus tend to force the shaft 30 to the right, as shown in Fig. 1, that is towards the spindles 26, and will retain the chuck blocks 28 and 29 in engagement.

For the purpose of disconnecting the clutch blocks 28 and 29 preparatory to the indexing operation of the work spindles, a sleeve 44 is mounted on the bracket 36 between the flange 38 and the frame of the machine, and this sleeve is adapted for rotary movement on this bracket. This sleeve is provided with an arm 45 carrying a roller 46 adapted for coating with a cam 47 carried by the cam drum 48. Mounted on the sleeve is a flange 49 provided with suitable openings through which the

shafts 30 extend, these shafts being provided with a flange 50 between which and the flange 49 is a suitable ball thrust bearing 51. The flange 49 is provided with a cylindrical portion 52 embracing the sleeve 44 which is provided with a plurality of inclined slots 53 in which are suitable rollers 54 carried on pins 55 mounted in the sleeve 44, so that when this sleeve 44 is rotated under the action of cam 47 on roller 46, the reaction of these slots with the rollers 54 will move flange 49 outwardly and will, at the same time, slide shafts 30 to the left as viewed in Fig. 1, to remove clutch block 29 carried thereby from engagement with the clutch block 28. These elements are held in this position by the cam 47 during the indexing operation of the turret and the spindles carried thereby, and when this indexing operation is completed roller 46 drops off cam 47 and springs 43 then force shafts 30 inwardly or to the right, as shown in Fig. 1 to again bring the blocks 28 and 29 into driving engagement.

The spindle drive shafts 30 are provided with one or more keys 56, and mounted on these shafts are a series of gears, in the present instance three, 57, 58 and 59, of different diameters which are longitudinally slidable on the shaft but rotate with the shaft because of the keys 56. These gears are each adapted to mesh with one of three gears 60, 61 and 62 formed on a sleeve 63 which is mounted to rotate on a short hollow shaft 64 supported at its opposite ends in the end of the tool supporting bar 113 and the frame 23 at the inner side of bracket 36. The gears 60, 61 and 62 are rotated by means of a main drive gear 66 which is connected to the sleeve 63 by any suitable means, and this main drive gear is driven by the main drive pinion 67. In the individual drives for the work spindles the gear 57 is adapted to mesh with the gear 60, gear 58 with gear 61, and gear 59 with gear 62. Thus it will be seen with a given rate of rotation the main drive gear 66 three different speeds may be given to each work carrying spindle depending on which of these gears are in mesh, and means is provided for shifting each set of gears 57, 58 and 59 independently on shaft 30 to give these three speeds to each spindle. In Figs. 15 and 16 is shown one form of means by which this may be accomplished.

For each set of gears there is a shipper rod mounted to slide in the frame these shipper rods 68 carry suitable forks 69 adapted to seat in grooves 70 in a collar 71 secured to each set of gears. These shipper rods project beyond the end of the frame where they are provided with suitable hand knobs 72 for shifting the rods and with them the gears 57, 58 and 59. For the purpose of holding the three gears in proper position the rod 68 is provided with suitable grooves 73 adapted to be engaged by a lug 74 carried by a pin 75 held against the rod 130

by a spring 76; there being a groove 73 for each of the three positions of the gears, and as there is one of these shifting rods for each set of gears the speed of each spindle may be changed independently of the other spindles.

The driving means for the main drive pinion 67 is shown in Fig. 6, this pinion being mounted to rotate with a shaft 77 on which is slidably mounted a clutch sleeve 78, this sleeve, however, being secured to rotate with the shaft by suitable keys 79. This clutch sleeve has driving teeth on its opposite ends adapted to mesh with similar teeth carried by gears 80 and 81 which gears are loosely mounted on the shaft. They are of different diameters and are located at opposite sides of the clutch sleeve at such a distance that the sleeve is in driving relation with only one of these gears at a time. A short shaft 82 is provided upon which are secured a series of gears 83, 84, 85 and 86, the gear 84 being in mesh with gear 81 and gear 86 in mesh with gear 80. Another shaft 87 is provided on which are mounted two sets of sliding gears 88, 89, and 90, 91, these two sets of gears, however, being mounted to turn with the shaft by suitable keys 92 and 93 respectively. By sliding gears 88, 89 on this shaft the smaller gear 88 may be meshed with gear 83 and larger gear 89 may be meshed with gear 85. Still another shaft 94 is provided on which is loosely mounted a pinion sleeve 95 carrying two pinions 96 and 97 adapted to mesh with gears 90 and 91 respectively, as desired, by shifting gears 90 and 91 on the shaft 87, and secured to this sleeve 95 is a clutch drum 98. Keyed to shaft 94 but longitudinally slidably thereon is a friction clutch cone 99 adapted to engage the drum 98 in the usual manner for driving the same, this cone being engaged or disengaged from the drum by means of a sleeve 100 co-acting with the clutch fingers 101, which engage the end of rod 101', the shaft 94 being driven from any suitable source of power by a belt pulley 102. The sleeve 100 is shifted automatically, after the completion of a cycle of operations on the work, by a fork 103 mounted to slide on a supporting rod 104, and shifted thereon by a lever carried by an upper shaft 105 having an arm 106 connected to an arm 107 secured on a shaft 108, which carries a second arm 109 with a roller 110 adapted to coact with cams 111 and 111' mounted on the cam drum 48, and so arranged that when the roller 110 is lifted by means of cam 111, sleeve 100 will be shifted to disconnect this main clutch drive. Cam 111' is arranged to throw the clutch in again at the proper time. The elements are so arranged that the clutch is disconnected before flange 49 is operated to disconnect the work spindle clutches 28, 29 and is not thrown in again until these clutches are again engaged or adapted for engagement after the indexing operation. When clutch 98—100 is disengaged

it will be obvious the power is disconnected from the work spindles, but as shaft 94 continues to rotate, the tool feed and indexing mechanism is operated independently of this clutch as will presently be described. For the purpose of manually throwing in or out this clutch, a hand lever 112 is mounted on the shaft 108.

The tools for performing certain of the machine operations are mounted on an improved type of support, and are also advanced by an improved feeding means. This tool support comprises a hollow bar 113. This bar or support has no connection with the turret 25 but is mounted on the frame entirely independent of this turret. The turret is provided with a longitudinal opening 114 therethrough through which this bar extends, but this opening is larger than the bar so that there is no connection between the two. The inner end of the bar is reduced at 115 and mounted in a bearing 116 in the frame 23 on the rear side of the turret and at its other end is reduced at 117 and mounted in a bearing 118 carried by the frame forwardly of the turret. Thus it will be seen the bar is rigidly supported by the frame at its opposite ends and on opposite sides of the turret, but it projects forwardly of the turret a sufficient distance to carry the tool slides indicated at 119 in proper relation to the chucks 27. This tool supporting bar is rigidly mounted in the frame and is stationary having no turning movement. Various means may be provided for securing it against rotation but I have shown a cap 120 secured to the outer side of the support 118 by suitable screws 121, and provided with dowel pins 122 extending through this cap into the end of the bar 113.

The bar is hollow and preferably cylindrical except where it is provided with guideways for the tool slides. In the present embodiment these guides are dovetails 123 extending longitudinally of the support and there are six of these dovetails, the support being substantially hexagonal at this point, as shown at Fig. 5. The tool slides 119 have longitudinally extending dovetail grooves to fit the dovetails on the support. In the center of each dovetail the support is provided with a slot 124 leading to the space at the center of the bar for the passage of a connecting means by which the tool slides are driven from the feed mechanism. Adjustably mounted on the slides by means of suitable bolts 125 extending through slots 126 are blocks 127 and these may be adjusted on the slides longitudinally thereof by means of a suitable screw 128 threaded into the blocks and secured to the slide by plates 129, the screw preferably being provided with a collar 130 having a scale to indicate the adjustments. Each block 127 is provided with a finger 130 extending through

the slots 124 and this finger is provided with a lug 131 adapted to seat in recesses 132 formed in the peripheries of feed collars 133 and 134. It will be noted from an inspection of Fig. 4 that the fingers 130 are not placed in the center of the blocks 127 but are placed between the center and one end of the block, and are so located that by merely reversing these blocks the finger may be connected with either of the collars 133 and 134, and as these two collars 133 and 134 are advanced by independent feeding means, the two slides and with them the tools may be fed in independent sets. Of course if all the slides are connected to a single collar, either 133 or 134, they will all be fed at the same speed and through the same stroke, but where different rates of feed and different strokes are required for some of the tools from certain of the other tools, they are connected to the other collar, which may be given a different rate of speed and a different stroke.

The means for imparting different rates of speed and different strokes to the collars 133 and 134 comprises a central longitudinally slidable bar 135 to which collar 133 is connected and a tube 136 embracing this bar to which collar 134 is connected, this tube being also longitudinally slidable and mounted in suitable bearings in the supporting bar 113. The bar 135 slides within this tube and is also provided with a bearing 137 at its free outer end in the cap 120. At their inner ends the bar 135 and tube 136 have connected therewith suitable blocks 138 and 139 respectively, these blocks carrying suitable rollers 140 adapted to coact with the cams 141 and 142 on the cam drum 48. Thus the rods or bars 135 and 136 are advanced and with them the tools which are connected therewith at a rate and a distance depending on the shape of the cams 141 and 142. At the end of the work strokes these elements with the tools are returned to their original positions by the cam blocks 143 and 144 respectively, carried on the surface of the drum 48.

Means is provided for changing the rate of rotation of cam drum 48 to give different rates of feed for the tools, and means is also preferably provided for increasing the speed of rotation of this drum during the return movement of the tool slides and also for indexing, to give a more rapid return and thus save time in preparing for the next operation. The means for doing this is shown more particularly in Fig. 6 in which the gears are shown diagrammatically and the shafts as in a common plane though their actual positions are shown in Fig. 7. On the drive shaft 94 is a spur gear 145 and a smaller gear 146 adapted to mesh respectively with gears 147, 148 formed on a gear sleeve 149, which is adapted to slide on shaft 150 but is keyed to rotate therewith by suitable keys 151. By

shifting this sleeve 149 either gears 145 and 147 or 146 and 148 may be brought into mesh as desired, this shifting being done by suitable means as a lever, not shown, on the outside of the machine. Also mounted on the shaft 150 are two gears of different diameter 152 and 153 adapted to mesh respectively with two gears 154 and 155 on a shiftable gear sleeve 156 slidable on shaft 157 but secured to turn therewith by keys 158. This sleeve 156 may be shifted in the same manner as sleeve 149. Also carried by the shaft 157 are two gears 159 and 160 adapted to mesh with sliding gears 161 and 162 respectively mounted to turn the shaft 163 by means of keys 164. Also mounted to turn with shaft 163 are two gears 165 and 166 of different diameters adapted to mesh with gears 167 and 168 respectively, slidably mounted on shaft 169 but secured to rotate therewith by suitable keys 170. Shaft 169 carries a bevel gear 171 which meshes with a second bevel gear 172 keyed to a sleeve 173 carried by a vertical shaft 174, this sleeve being adapted to rotate on this shaft. Upon the upper end of this shaft is a toothed ratchet 175 (Figs. 6 and 9) within a collar 176 which carries a pawl 177 normally held in engagement with the teeth of the ratchet by a spring 178 so that as the ratchet is rotated in a counter-clockwise direction as viewed in Fig. 9, it will, through the pawl, rotate collar 176, and as collar 176 is keyed to vertical shaft 174 this shaft will be driven thereby. Mounted on this shaft to rotate therewith is a worm 179 meshing with worm gear 180 loosely mounted on horizontal shaft 181, which gear is on a sleeve having at one end thereof suitable clutch teeth 182 adapted to mesh with a clutch sleeve 183 slidably mounted on the shaft 181 but is secured to rotate therewith by suitable keys 184. This sleeve has clutch teeth 185 on its other end adapted to mesh with similar teeth 186 on another worm gear 187 also loosely mounted on shaft 181. Gear 187 meshes with a worm 188 on shaft 189 which extends transversely through the frame of the machine as shown in Figs. 2 and 17 provided with square ends 190 to receive a hand crank 191. The shaft 181 is provided with a pinion 192 meshing with internal gear 193 on the cam drum 48 for rotating this drum. When clutch sleeve 183 is shifted to the left to engage with worm gear 180, shaft 181 on the cam drum will be driven from the vertical shaft 174, but when this sleeve 183 is in engagement with gear 187 shaft 181 and the cam drum may be rotated by hand through the shaft 189. As the indexing mechanism for the spindle carrying turret 25 is operated from the shaft carrying the cam drum 48, by mechanism presently to be described, it will be plain that through this mechanism just described the work spindles may be indexed by hand if desired, 130

and it also allows feeding of the tools by hand for setting up the machine and adjusting.

For the purpose of increasing the rotation of the cam drum 48 for the purpose of giving 5 a quicker return to the feed mechanism and also quicker indexing of the work spindles, loosely mounted on the upper end of vertical shaft 174 is a sleeve 194 also having a bearing in the frame of the machine, and carried by this sleeve is a beveled gear 195 meshing with a beveled gear 196 secured to shaft 94. At its opposite end the sleeve 194 carries a clutch drum 197. Secured on the shaft 174 so as to rotate therewith but slidable 15 thereon is a clutch flange 198 adapted to be moved to and from driving engagement with drum 197 by means of fingers 199 and sleeve 200. Thus it will be seen that when this clutch is engaged the shaft 174 will be driven 20 directly by gears 195 and 196 and at a greater speed than through the gear mechanism 145 to 172, and while this clutch is engaged, the collar 176, as it is secured to the shaft 174, will rotate faster than the normal driving 25 means therefor, which is sleeve 173, but it is allowed this rapid movement through the pawl and ratchet 175—177. The sleeve 200 is shifted on the shaft to engage the clutch 197 and 198 automatically at the end of the 30 feed stroke of the tools by the lever 201 shown in Figs. 17 and 19. This lever is automatically operated at the correct time by suitable cams 202 on disc 202 carried on the cam shaft 203. 35 In the forward part of the machine is provided means for shifting the clutch sleeve 183. This comprises a longitudinally movable slidable rod 204 bearing an arm 205 including a fork adapted to enter the groove 206 in the sleeve 183. Secured to this rod is a collar 207, and between this collar and the frame is a spring 208 tending to move the rod to the right, as viewed in Fig. 18, and hold sleeve 183 in engagement with the worm gear 187. 40 Pivoted on the frame is a hand lever 209 provided with a fork 210 engaging in a sleeve 211, which sleeve is slidably mounted on the rod 204, and the end of this sleeve is adapted to engage an upper inclined wall upon a lug 212 on a catch plate 213 carried on a lever 214 fulcrumed at 215. The upper end of this catch plate is adapted to enter a notch 216 in the rod 204 to hold it in its left hand position with the sleeve 183 in engagement with 45 worm gear 180, and this catch plate is connected with a spring 217 which tends to raise it toward the rod and hold it in said notch. Thus by lifting upwardly on the handle 218 of lever 209 the end of sleeve 211 will be 50 forced against the lug 212 pressing same downwardly out of engagement with the notch 216. As the rod 204 is thus no longer secured, the spring 208 will force the same to the right as shown in Fig. 18, moving sleeve 55 183 out of engagement with gear 180 and into engagement with gear 187, stopping the automatic feed and connecting the cam drum with the hand feeds 189 and 191. Means is also provided for automatically removing the catch plate 213 from the notch 216, comprising a cam 219 carried by the shaft 203 and adapted at the proper time to engage a finger 220 pivoted to the lever 214 at 221, which finger is normally held against a stop pin 222 by spring 223 but will yield in the opposite direction should the shaft 203 be rotated backwards by the hand operating mechanism 189—191. Thus there is a single hand control for connecting the power with the feeding and indexing mechanisms in a locked relation, and by the same control the locked connection may be released at any point in the cycle of operation. There is thus provided hand controlled means for starting or stopping the feeding and indexing mechanism at any point in its cycle and also automatic means for stopping the feeding and indexing mechanism at a predetermined point in its cycle of operation. 60 The means for indexing the turret and the work carrying spindles is indicated in Figs. 10 and 11, and comprises the well known Geneva movement. Carried by the turret at its inner end are a series of blocks 224 having longitudinal grooves 225 therein, these blocks being arranged so that the grooves run radially of the turret, and they correspond in number to the number of spindles, in the present instance six. Carried on the cam drum shaft 203 is a cam disc 226 having an arm 100 carrying a roller 227 adapted upon each revolution of the shaft to enter a groove 225 in one of the blocks and rotate the turret one sixth of a revolution. Means is provided for locking the turret in the proper position to bring the work carrying spindles 26 into alignment with the spindle drive shafts 30. For this purpose, on the periphery of the turret are mounted a plurality of plates 228 having notches 229 therein adapted to receive the lug 230 of a locking piece 231 mounted to reciprocate in the frame. This locking piece is automatically withdrawn from the notches 229 by means of a lever 232 fulcrumed in the frame at 233 and provided at its upper end 105 with a head 234 adapted to engage a shoulder on the blocking piece 231 for retracting the same, or moving it to the right as shown in Fig. 2. This lever is operated at the proper time or immediately before roller 227 engages a block 224, by means of a cam lug 235 carried on the disc 226 adapted to engage a roller 236 carried by the lever 232. Thus it will be apparent that as the disc 226 rotates with shaft 203 and the cam drum 48, at the 110 end of the cycle cam lug 235 will retract locking piece 231 unlocking the turret which will then be rotated a partial revolution to advance each work carrying spindle to a position in alignment with the next spindle driv- 115 120 125

ing shaft. After the proper movement has been given to the turret, roller 236 will leave block 235 allowing the locking piece 231 to be moved inwardly to locking position by a spring 237. After this has taken place cam 47 will allow engagement of the spindle driving shafts 30 with the clutch blocks 28 on the work carrying spindle ready for driving them on the next operation.

16 There are also preferably provided two tool slides on opposite sides of the frame for carrying suitable facing tools or the like, these tools moving transversely of the work carrying spindles and are shown with their operating means in Figs. 1, 2 and 3. Mounted on the frame so that they may be adjusted longitudinally thereof are slides 238 and 239 which are normally stationary, adjusting screws therefor being shown at 240, and carried by these slides are tool carrying slides 241 and 242 which move transversely of the axes of the work carrying spindles. They are reciprocated by suitable guides carried by the slides 238 and 239, by means of arms 243 and 244 respectively carried on shafts 245 and 246. These shafts are operated to impart the feeding and return movements to the slides 241 and 242 by a cam plate 247 carried on the shaft 203, this cam plate being provided with cams on its opposite faces indicated at 248 and 249 coating with rollers 250 and 251 respectively on arms 252 and 253 secured to the shafts 245 and 246 respectively.

17 It is believed the operations of the various devices will be clear from the foregoing description. By means of the specific drive shown for the work operating spindles, not only may the rate of rotation of these spindles be varied as a whole, but the speed of each spindle may be regulated independently of the other spindles. Also through the train of gearing shown in Fig. 6 the rate of rotation of the cam drum 48 and shaft 203 may be varied. By using different cams 141 and 142 the rate of feed and the length of stroke imparted to blocks 133 and 134 and to the two slides connected therewith may be varied. By means of the cam 111 shafts 108 and 105 and clutch 98, the main drive for the work spindles is automatically disconnected at the end of a cycle, or during the indexing operation to facilitate connection and disconnection of clutches 28-29, and may be disconnected at any time by the hand lever 112. Through the clutch drive 197 automatically operated by lever 201 the tools are automatically returned at the end of an operation to the position at the beginning of the operation by an accelerated movement. By means of the mechanism shown in Figs. 17 and 18 the shaft 181 driving cam drum 48, cam drum shaft 203 is automatically disconnected from the power feed at the end of a cycle and connected to the hand feed 191, hand operated means 209 being provided for also effecting

this change at any time desired. Upon continued rotation of the cam drum the spindle driving shafts 30 are automatically disconnected from the work carrying spindles by means of cam 37 operating through flange 49, 70 and after the turret with the work carrying spindles has been advanced to the next position through the Geneva movement mechanism, as shown in Figs. 10 and 11, these spindle drive shafts are automatically returned 75 to driving engagement with the spindles. Still further that as the cam drum and its shaft are rotated the various tool slides with the tools carried thereby are automatically advanced and retracted by their respective 80 cam mechanisms, the machine being semi-automatic in that the rough work is placed in a chuck and the finished piece removed by the operator, and although the operations are performed automatically still the machine is 85 under the control of the operator at all times. The disconnection of power drive at the end of each cycle prevents indexing of the turret and thus injuring the machine or the operator should a cycle be completed before the operator has finished placing a rough piece in the chuck. It will further be apparent from Fig. 1 that all the driving mechanism for the spindles and the cam drum shaft are located 90 to the left, as viewed in this figure, or to the rear of the turret, leaving the front of the machine forwardly of the turret clear for the various tools, inspection of the work, and to facilitate removal and insertion of the work, 95 the only drive mechanism that is located at this side of the turret being that for the slides 241 and 242. This leaves a short machine forwardly of the turret allowing the operator to quickly and easily pass from and to either 100 side of the machine. The tubular mounting for the tools, that is supporting bar 113, gives a very rigid support for the same on the frame, and at the same time allows placing of the feed mechanism for the tools carried by this bar within the same where it is out of 105 the way and does not take up space around the tool supporting bar.

110 Having thus set forth the nature of my invention, what I claim is:

1. In a machine of the class described, a supporting frame, a rotatable spindle carrying turret mounted in said frame, and a tool support extending through the turret and supported by the frame on opposite sides of the turret independently of the turret. 115
2. In a machine of the class described, a supporting frame, a rotatable spindle carrying turret mounted in said frame and provided with an opening therethrough, a tool support extending through said opening and spaced from the walls thereof, means for supporting the tool support in the frame at the back of the turret, means for supporting the tool support on the frame at the front of the turret, and tool carrying means on the tool 120
3. In a machine of the class described, a supporting frame, a rotatable spindle carrying turret mounted in said frame and provided with an opening therethrough, a tool support extending through said opening and spaced from the walls thereof, means for supporting the tool support in the frame at the back of the turret, means for supporting the tool support on the frame at the front of the turret, and tool carrying means on the tool 125

support between the turret and the latter supporting means.

3. In a machine of the class described, a supporting frame, a rotatable spindle carrying turret mounted in said frame, a hollow tool support extending through the turret and supported by the frame on opposite sides of the turret, tool carrying means slidably mounted on the tool support, and means within the tool support for sliding said carrying means.

4. In a machine of the class described, a supporting frame, a rotatable spindle carrying turret mounted in said frame, a tool support extending through the turret and supported by the frame on opposite sides of the turret, movable tool carrying means on the tool support at the front of the turret, and feeding means for said tool carrying means on the opposite side of the turret.

5. In a machine of the class described, a supporting frame, a rotatable spindle carrying turret mounted in said frame, a hollow tool support extending through the turret and supported by the frame on opposite sides of the turret, one or more tool carrying slides mounted on said support, means within the support for operating said slides, and means located back of the turret for operating said slide operating means.

6. In a machine of the class described a hollow tool support, a plurality of tool slides mounted on said support, a plurality of slide operating members within said support and adapted for independent operation, means for operating said members, and means for connecting the slides to one or the other of said members.

7. In a machine of the character described, a supporting frame, a rotatable spindle carrying turret mounted in said frame, a hollow tool support extending through the turret and supported by the frame on opposite sides of the turret, movable tool carriers mounted on the tool support, means within the support for moving said carriers, and means for operating said means.

8. In a machine of the class described a hollow tool support, a plurality of tool slides mounted on said support, a plurality of slide operating members within said support and adapted for independent operation, means for operating said members, and means whereby the slides may be connected to either member.

9. In a machine of the class described a hollow tool support, a plurality of tool slides mounted on said support, a plurality of concentrically mounted longitudinally reciprocable slide operating members in said support and adapted for movement relatively to each other, means for operating said members, and means for connecting the slides to said members.

10. In a machine of the class described a hollow tool support, a plurality of tool slides

mounted on said support, a plurality of concentrically mounted slide operating members in said support and adapted for independent operation, means for operating said members, and means for connecting the slides to said members.

11. In a machine of the class described, a supporting frame, a rotatable spindle carrying turret mounted in said frame, a hollow tool support extending forwardly of said turret, a plurality of tool carrying slides mounted on said support, and a plurality of independently operable means within the support for operating said slides.

12. In a machine of the class described, a supporting frame, a rotatable spindle carrying turret mounted in said frame, a hollow tool support extending forwardly of said turret, one or more tool carrying slides mounted on said support, means within the support for operating said slide or slides, and means located back of the turret for operating said means to feed the tools.

13. In a machine of the class described, a supporting frame, a rotatable spindle carrying turret mounted in said frame, a hollow tool support extending forwardly of the turret, a plurality of tool carrying slides mounted on said support, a plurality of relatively movable longitudinally reciprocable means in said support, means for connecting the slides to one or the other of said reciprocating means, and means for operating the reciprocating means.

14. In a machine of the class described, a supporting frame, a rotatable spindle carrying turret mounted in said frame, a hollow tool support extending forwardly of the turret, a plurality of tool slides mounted on said support, a plurality of slide operating members within said support and adapted for independent operation, means for operating said members, and means whereby the slides may be connected to either member.

15. In a machine of the class described, a supporting frame, a rotatable spindle carrying turret mounted in said frame, a hollow tool support extending forwardly of the turret, a plurality of tool slides mounted on said support, a plurality of slide operating members within said support and adapted for independent operation, means for independently operating said members for feeding the tools, and means whereby the slides may be connected to either of said members.

16. In a machine of the class described, a frame, a rotatable turret mounted in the frame, a plurality of work carrying spindles carried by said turret, a tool slide carrier extending through the turret, and supporting means on the frame for both ends of the tool slide carrier on opposite sides of the turret.

17. In a machine of the class described, a rotatable turret, a plurality of work spindles carried by said turret, a hollow tool support,

a plurality of tool slides on said support movable longitudinally of said spindles, means within the support for independently operating said slides, a tool carrying slide operable transversely to the axes of the spindles, and means for operating the latter slide independently of the longitudinally movable slides.

18. In a machine of the class described, a plurality of work carrying spindles, a plurality of tool slides, a plurality of cams, a plurality of operating means operated by the cams, and means whereby one or more of said slides may be connected to either operating means.

19. In a machine of the class described, a rotatable turret mounted to turn about a horizontal axis, a plurality of horizontal work spindles mounted in said turret, a tool support extending forwardly of the turret, a plurality of tool carrying means movably mounted on the support, driving means for the spindles located to the rear of the turret, means for independently operating the tool carrying means located within the support, and means located to the rear of the turret for driving the operating means.

20. In a machine of the class described, a rotatable turret, a plurality of work spindles mounted in said turret and positioned about the axis thereof, driving means for said spindles comprising a plurality of driving gears of different diameters coaxially with the turret, a plurality of gears of different diameters coaxial with the spindles and mounted on axially movable shafts, clutches between the shafts and the spindles, means for shifting the shafts to operate the clutches, and means for causing relative axial movement between the driving gears and the spindle gears to bring different diameters of gears into mesh to give different rates of rotation to the spindles.

21. In a machine of the class described, a rotatable turret, a plurality of work spindles mounted in said turret and positioned about the axis thereof, a plurality of driving gears of different diameters mounted coaxially with the turret, means for driving said gears, a plurality of sets of gears of different diameters coaxial with the respective spindles and adapted to mesh with certain of the driving gears, a longitudinally movable shaft upon which each set of gears is mounted, clutch drives between said shafts and the spindles, automatic means for shifting the shafts to operate the clutches, and independent means for shifting each set of spindle gears to bring them into mesh with different driving gears and vary the rate of rotation of the respective spindles independently.

22. In a machine of the class described, a rotatable turret, a plurality of work spindles carried by said turret, a hollow tool support forwardly of the turret, a plurality of tool

carrying means movably mounted on the support, driving means for the spindles rearwardly of the turret, said driving means including means for independently varying the rate of rotation of the individual spindles, a plurality of means for independently operating the tool carrying means located within the support, and means located to the rear of the turret for driving the operating means.

23. In a machine of the class described, a rotatable turret mounted to turn about a horizontal axis, a plurality of work spindles carried by said turret, a hollow tool support, means forwardly of the turret, driving means for the spindles rearwardly of the turret, automatic means for indexing the turret, automatic means for disconnecting the spindle driving means during indexing of the turret, a plurality of independent tool operating means within the support, and driving means for the operating means located to the rear of the turret.

24. In a machine of the class described, a plurality of work spindles, drive shafts for said spindles, clutch connections between the shafts and spindles, a bracket, a rotatable sleeve mounted on said bracket, a ring or flange mounted on said sleeve and having connection with said shafts, and coacting cam means carried by said sleeve and flange arranged upon rotation of the sleeve to disconnect said clutch connections.

25. In a machine of the class described, a plurality of work spindles, drive shafts for said spindles, clutch connections between the shafts and spindles, a bracket, a rotatable sleeve mounted on said bracket, a ring or flange mounted on said sleeve, said shafts extending through said flange and connected thereto, coacting cam means carried by the flange and sleeve arranged to disconnect said clutch connections upon rotation of said sleeve, and means for automatically rotating said sleeve at a predetermined time.

26. In a machine of the class described, a work spindle, a drive shaft for said spindle in alignment therewith, a clutch connection between the shaft and spindle, a thrust pin extending longitudinally into the shaft from the other end thereof, a spring in the shaft reacting against the pin and shaft and tending to hold said clutch connection in engagement, a support for the free end of said pin, means for sliding the shaft on said pin to disconnect said clutch connection, and means for driving said shaft.

27. In a machine of the class described, a rotatable turret, a plurality of work spindles carried by said turret, an indexing mechanism for said turret, a power drive for said indexing mechanism including a clutch, automatic means connected with the indexing mechanism for releasing said clutch at a predetermined point in the cycle of operation, and a manual control for the clutch adapted

to release the clutch independently of the automatic means.

28. In a machine of the class described, a rotatable turret, a plurality of work spindles carried by said turret, one or more tool supports, feeding mechanism for the tool supports, indexing mechanism for the turret, a power drive for said feeding and indexing mechanisms including a clutch automatic means connected with the indexing mechanism to release the clutch at a predetermined point in a cycle of operations, and a manual control for the clutch adapted to release the clutch independently of the automatic means to stop the feed and indexing mechanisms at any point in the cycle of operation.

29. In a machine of the class described, a rotatable turret, a plurality of work spindles carried by said turret, an automatic indexing mechanism for said turret, one or more tool supports, feeding mechanism for the tool supports, driving means for indexing and feed mechanisms including a clutch, and manually controlled means for operating said clutch for starting and stopping the feeding and indexing mechanisms at any point in a cycle of operations.

30. In a machine of the class described, a rotatable turret, a plurality of work spindles carried by said turret, a hollow tool support forwardly of the turret, tool carrying means movably mounted on the support, driving means for the spindles rearwardly of the turret, said driving means including means for independently varying the rate of rotation of the individual spindles, means for operating the tool carrying means located within the support, and means located to the rear of the turret for driving the operating means.

31. In a machine of the class described, a rotatable turret mounted to turn about a horizontal axis, a plurality of work spindles carried by said turret, a hollow tool support forwardly of the turret, driving means for the spindles rearwardly of the turret, automatic means for indexing the turret, automatic means for disconnecting the spindle driving means during indexing of the turret, tool operating means within the support, and driving means for the operating means located to the rear of the turret.

32. In a machine of the class described, a supporting frame, a rotatable turret mounted in the frame, a plurality of work spindles carried by said turret, a driving shaft for each spindle mounted in the frame in axial align-

ment with the spindle, a driving connection between the shaft and spindle adapted to permit limited relative movement between them, and gear drives for the respective shafts.

33. In a machine of the class described, a supporting frame, a rotatable turret mounted in the frame, a plurality of work spindles carried by said turret, a driving shaft for each spindle mounted in the frame in axial alignment with the spindle, a detachable clutch driving connection between the shaft and its spindle, a gear on the shaft, and a driving gear meshing therewith.

34. In a machine of the class described, a supporting frame, a rotatable turret mounted in the frame, a plurality of work spindles mounted in said turret and positioned about the axis thereof, a driving shaft for each spindle mounted in the frame in axial alignment with the spindle, a detachable clutch driving connection between the shaft and the spindle, driving gears in axial alignment with the turret, and gears on the shafts meshing with the driving gears.

35. In a machine of the class described, a supporting frame, a rotatable turret mounted in the frame, a plurality of work spindles carried by the turret, driving shafts for the respective spindles mounted in the frame, detachable driving connections between the driving shafts and their corresponding spindles, a plurality of driving gears of different diameters on a shaft coaxial with the turret, a gear on each driving shaft meshing with one of said driving gears, means for disconnecting the driving connections between the shafts and the spindles, and means for indexing the turret.

36. In a machine of the class described, a supporting frame, a rotatable turret mounted in the frame, a plurality of work spindles carried by the turret, driving shafts for the spindles mounted in the frame in axial alignment with the respective spindles, a plurality of driving gears of different diameters mounted on a shaft coaxial with the turret, gears on the drive shafts meshing with the driving gears, a detachable clutch driving connection between the respective driving shafts and the corresponding spindles, means for shifting the driving shafts longitudinally to disconnect and connect the clutches, and means for indexing the turret.

In testimony whereof I affix my signature.

ARTHUR J. LEWIS.
